UNITED STATES PATENT OFFICE.

JOSEPH WOLFF, OF NEW YORK, N. Y., ASSIGNOR TO SONORA PHONOGRAPH CORPORATION, A CORPORATION OF NEW YORK.

DESIGN FOR A STYLUS FOR PHONOGRAHS.

50,640.

Specification for Design.

Patented Apr. 17, 1917.

Application filed November 27, 1914. Serial No. 874,343. Term of patent 7 years.

To all whom it may concern:

Be it known that I, JOSEPH WOLFF, a subject of His Majesty the King of Great Britain, residing in the borough of Manhattan, city, county, and State of New York, have invented a new, original, and ornamental Design for a Stylus for Phonographs, of which the following is a specification, reference being had to the accompanying drawings, forming a part thereof.

My invention is illustrated in the accompanying drawings in which—

Figure 1 is a top plan view of a stylus embodying my invention;

Fig. 2 is a side elevation thereof; and Fig. 3 is a view at right angles to Fig. 2.

I claim:

The ornamental design for a stylus for phonographs, as shown.

This specification signed and witnessed this 20 day of November, 1914.

JOSEPH WOLFF.

Witnesses:

JOHN L. LOTSCH,
GEO. J. HANSON.
